PRODUCTION OF MIDDLE DISTILLATES

Elroy Merle Gladrow, Baton Rouge, Ralph Burgess Mason, Denham Springs, and Charles Newton Kimberlin, Jr., and William Floyd Arey, Jr., Baton Rouge, La., assignors to Esso Research and Engineering Company, a corporation of Delaware

Application July 31, 1956, Serial No. 601,180

6 Claims. (Cl. 208—46)

The present invention relates to the processing of hydrocarbon oils to produce higher-boiling hydrocarbons, and more particularly to a combination process for converting naphthas boiling in the gasoline range into middle distillate fractions suitable as heating oils, jet fuels, tractor fuels and the like.

The principal object of the present invention is to provide a process for converting low octane or unstable naphthas and other low octane components of gasoline into material of higher value and higher boiling range.

With the introduction of high compression ratio automobile engines the octane requirements of gasoline has been steadily increasing, and this has resulted in the narrowing of the choice of constituents that can be used as high octane gasoline blending agents. Much virgin naphtha and naphtha resulting from the catalytic cracking from gas oil, hitherto employable in gasoline blends suitable for engines of moderate compression ratios, can no longer be used for this purpose. Similarly, refinery processes such as fluidized coking of heavy oils and residua and visbreaking produce naphthas that are unstable, with resultant sludge forming characteristics, and are of too high sulfur content for satisfactory use.

Concomitant with the accumulation of these naphtha streams and products in the refineries, there has grown in recent years increased demands for hydrocarbons boiling in the middle distillate range of from about 300° to 750° F. The rapid growth of heating oil installations both in the United States and abroad, and the increased use of heating oil for air conditioning equipment has made demands upon refineries that has caused the supply of heating oil to be out of balance with that of motor gasoline. The increased use of jet engines, which require a higher boiling fuel than gasoline fractions, has aggravated this unbalance.

Heretofore middle distillate fuels have been produced as by-products in the manufacture of gasoline, and such fuels of relatively high quality could be obtained from fractions of the virgin crude oil or from the cracking of virgin crude oil or from mixtures of virgin and cracked products. The phenomenal increase in demand for distillate fuels brought about by the factors enumerated above, as well as the increase in diesel fuel requirements, has presented, therefore, a serious problem to the oil refining industry.

Middle distillates, or distillate fuels, usually boil in the range of about 350—750° F., the so-called heater oils boiling chiefly in the range of 350—550° F., while diesel fuels boil at about 400—650° F. It is desirable to have these products of low sulfur content and low sludging characteristics.

In accordance with the present invention, refinery imbalances between gasoline and heating oil demands and stocks are restored by catalytic conversion of naphtha fractions into middle distillates. This is in a sense the reverse of the hitherto trend of petroleum refining where the gasoline fraction was the desired product, and where low grade gasoline fractions were upgraded to high anti-

2

knock material by such processes as reforming or isomerization. The present invention involves principally conversion of the naphtha into middle distillate by catalytic condensation reaction involving formation and reaction of an olefinic intermediate, if a completely saturated naphtha, such as casinghead or virgin naphtha is initially fed into the process. In brief compass, it has been found that high yields of high quality low gravity middle distillates may be obtained by the catalytic conversion of low quality naphthas in the presence of a solid catalyst of the mixed oxide type, such as a magnesia-silica or a silica-alumina catalyst at elevated temperatures and pressures. In one embodiment of the present invention naphtha is thermally cracked to a moderate or relatively low degree of conversion, forming substantial quantities of olefins which are then passed to the catalytic conversion zone. In another embodiment low grade naphtha, such as catalytic naphtha or coker naphtha is mixed in minor amounts with virgin or casing head naphtha prior to conversion. Though the presence of olefins is a necessary intermediate, there is a disappearance of naphtha, and it is probable that under the reaction conditions, polymerization of olefins is accompanied by substantial alkylation of olefinic naphtha with the saturated naphtha. In still another embodiment, wherein unstable naphthas such as visbreaker naphtha or fluid coker naphtha are being processed, no virgin naphtha need be concomitantly processed.

The invention will be more readily understood when read in conjunction with the more detailed description hereinafter wherein reference will be made to the accompanying drawing which is a diagrammatic illustration of a preferred embodiment of the invention. Turning now to the drawing, a naphtha feed comprising low quality low octane naphtha, such as virgin naphtha, casing head naphtha or other substantially paraffinic or saturated naphtha is passed via line 2 to thermal cracking zone 4. Conditions within zone 4 are maintained such as to insure relatively low feed conversion and high olefin selectivity. Preferred conditions are relatively mild conditions of temperature and pressure. Thus it is preferred to operate the cracking zone at temperatures in the range of 950° to 1150° F. at pressures in the range of 50 to 400 p.s.i.g. At times, however, it may be expedient to operate the cracking zone at the pressure of the subsequent part of the system because a compressor will be required between the cracking zone and the reactor system if the two are to operate at their respective optimum pressures. When it is desired to strike such a balance and operate with a minimum of compression equipment, the cracking zone pressures may be as high as 1200 p.s.i.g. The nature of the cracking operation is such that for the same conversion the feed rate varies over wide limits with variations in temperature and pressure. In general the liquid feed is maintained in the range of 0.3 to 6 liquid volumes per volume of cracking zone. Although expressed as liquid rate, it is understood that with naphtha feeds the conditions in the cracking zone are essentially those of vapor phase.

The effluent from cracking zone 4 is passed via line 6 to gas separator 10. Low boiling cracked gases are withdrawn through line 11, while the liquid cracked naphtha now containing a substantial amount of olefins, and which naphtha may have a product bromine number of 30—50, is passed via line 12 and heat exchanger 14 to naphtha conversion zone 20.

The operating conditions of zone 20 to obtain good yields are critical. It was found to be essential to employ and maintain a liquid phase operation. A heavy build up of tar on the catalyst normally occurs, and only by maintaining a liquid phase was it found possible continuously to remove polymer and tar on the catalyst as

formed, thereby prolonging catalyst life and increasing the extent of condensation of the naphtha constituents. The desired liquid phase condition may be achieved by various means. One such and preferred is maintenance of an up-flow operation. Recycle of a portion of the higher boiling component is another.

Within zone 20 there is maintained a naphtha conversion catalyst of the oxide or mixed oxide type, preferably a silica-alumina or a silica-magnesia catalyst of the type conventionally employed for cracking hydrocarbons catalytically. These are well-known per se, as is also their method of preparation. If desired, the catalyst may be activated with minor amounts of known activating agents such as $AlCl_3$, BF_3 , and the like. Reaction conditions within conversion zone 20 include high pressures, above about 600 p.s.i.g., and preferably above about 750 p.s.i.g., up to 3000 p.s.i.g. and higher. Temperatures in the range of about 300-750° F. and liquid feed rates of 0.2 to 2 v./v./hr. may be used.

Though a fixed bed catalyst may be maintained within reactor 20, frequent reactivation would be necessary to maintain the bed at a high conversion level. A more satisfactory operation is the maintenance of the catalyst in suspension in the liquid phase operation. About 1% to 25% catalyst on the total feed, and preferably about 3% to 10%, may be employed. The upflowing naphtha stream admitted through line 16 maintains the catalyst in constant suspension.

The reaction product is withdrawn from the top of reactor 20 by line 21 and passed to product filtration-settling zone 34. Filtered product is passed via line 24 to product fractionator 26. The desired middle distillate fraction is withdrawn through line 30, while unreacted naphtha may be recycled through line 28 to the cracking zone or, if desired, in part to conversion zone 20 through lines 28 and 46.

The catalyst separated in filtration zone 34 is withdrawn downwardly through line 36 and passed to a fluidized solids regeneration zone 40. In this zone, the catalyst to be regenerated is maintained as a fluidized bed of solids by an upflowing regeneration gas stream, such as air, admitted through line 48. The regeneration is carried out at temperatures of about 900° to 1200° F., and the hot regenerated catalyst passes downwardly through standpipe 50 and is passed via aerated lines 42 and 44 through heat exchanger 14 to lockhopper 22, whence it is returned to the reactor 20 through line 18. The fluid solids transfer is effected through a gas lift by an inert gas, such as nitrogen, steam, natural gas or the oxides of carbon, being introduced through line 52 and removed by line 54.

The process of the present invention may be modified in many features without departing from its spirit. Thus, if the naphtha to be converted is appreciably olefinic, with a bromine number of about 60 or higher, the thermal cracking step may be omitted and the naphtha passed directly into conversion zone 20 through lines 2, 3 and 12. Similarly, it may be desirable to add mixed streams of olefinic and substantially paraffinic low octane naphthas directly into the conversion zone, for the resulting middle distillate is formed essentially by alkylation as well as polymerization reactions. On the other hand, it may also be desirable to add olefinic naphthas as such, or as the sole feed, to the thermal cracking zone. This is particularly true where these naphthas are unstable.

Besides the catalysts named, other suitable oxide catalysts are natural clays, acid-treated clays, and fluoride-treated clays. However, a diatomaceous earth catalyst impregnated with phosphoric acid, a well-known polymerization catalyst, was not found to be suitable for this service.

Fractions boiling higher than the middle distillate may be removed through line 32 and may also be recycled to the thermal cracking zone to make further middle distillate.

The process of the present invention may be more clearly illustrated in the following specific examples.

Example 1

A coker naphtha having a boiling range of 170° to 400° F. and a bromine number of 106 was agitated in a shaker autoclave with a commercial silica alumina catalyst under different conditions of temperature. Also a similar test was made at one temperature condition with a feed comprising 29% by weight of the same coker naphtha and 79% of virgin naphtha. Results of these experiments are set forth below:

[3-liter shaker autoclave unit, 6 hours' operation, 20 wt. percent silica-alumina.]

Feed	Coker Naphtha			29% Coker Naph., 71% Lt. Virgin Naphtha
Temp., ° F.	450	600	750	750
Pressure, P.s.i.g.	125	350	900	1,100
Feed				Feed
Liquid Prod. Dist., Wt. Percent:				
IBP-350° F.	78	37.6	20.8	60.3
350-430° F.	22	17.4	50.9	18.7
430 + Bottoms	45.0	28.3	21.0	6.4
Inspections, Total Prod.:				10.0 (34.5)
Gravity	49	39	46	54
Bromine No.	106	32	24	9
				31

¹ Value in parentheses is on coker naphtha basis.

A substantial increase in the 430° F. plus product is noted. Under conditions of the test the product distribution and yield change with temperature, but comparison of column 4 with column 3 demonstrates greater selectivity in presence of an added non-olefinic naphtha, i.e., more middle distillate was made than would be predicted or accounted for on the basis of the coker naphtha content alone.

Example 2

The same feed stock was passed in a continuous operation over a fresh charge of the silica-alumina catalyst with results as tabulated below:

[Coker naphtha feed (170-400° F. boiling range, 106 Br. No.), 400 cc. silica-alumina catalyst, feed rate 1 v./v./hr.]

Temperature, ° F.		450		600	
		5-11	12-19	1-5	12-175
Run, Hours.	(Feed)				
Product Dist., Wt. Percent:					
IBP-350° F.	78	49.5	56.7	50.7	54.5
350-430° F.	22	19.1	23.2	17.3	18.2
430-650° F.	16.9	10.8	20.8	17.7	17.7
650-850° F.	10.2	6.5	8.9	7.6	7.6
850-1,015° F.	3.0	2.0	1.5	1.3	1.3
1,015 + Bottoms	1.3	0.8	0.8	0.7	0.7

Thus, substantial yields of 350-650° F. product are demonstrated with only small amounts of extremely high boiling 850° F. plus product.

Example 3

A catalytically cracked naphtha having a boiling range of 105-340° F. and a bromine number of 95 was catalytically treated at 450° F. and 500° F. in continuous fixed bed operation at 800 p.s.i.g. and 1 volume of feed per volume of catalyst per hour. The catalysts used were a fresh 13% Al_2O_3 -87% SiO_2 mixed oxide catalyst and "UOP" poly catalyst (phosphoric acid on kieselguhr). The data follow.

Temperature, ° F...	450			500		
	SiO ₂ —Al ₂ O ₃	"UOP"	SiO ₂ —Al ₂ O ₃	"UOP"	SiO ₂ —Al ₂ O ₃	"UOP"
Tot. Vol. Feed Processed/Vol. Cat.	18	30	21	33	58	70
Vol. Percent 350° F. + Product	25	24	18	17	22	23
Br. No. of Naphtha Residue	44	63	65	43	44	54
	64			64		

These data show the advantages of using the mixed oxide type catalyst in such an operation for producing middle distillate from naphthas comprising olefins.

To illustrate further the advantages for the mixed oxide type catalyst, some of the naphtha residue (having a bromine number of 60) from the above tests was composited and a second pass made through the catalytic zone. Approximately 18% of the original naphtha had been converted to middle distillate in the first pass. The tests were conducted at 1 v.v./hr., 500° F., and 800 p.s.i.g. The results follow.

Catalyst.....	13Al ₂ O ₃ —87SiO ₂	"UOP"
Vol. of feed processed/vol. cat.....	16	16
Br. No. of Naphtha Residue.....	12	41
Vol. Percent 350° F. + Yield: On feed.....	17	10
Total (first plus second pass).....	31	26

These data show a consistent advantage of higher yields of middle distillate over the silica-alumina catalyst.

The recycle feature which gave added yield can be achieved, or at least in part, by employing partial condensation and recycling the uncondensed low boiling compounds.

Example 4

A thermal cracking coil was installed on the upstream side of a catalytic converter and was operated at 1000° F. and 1025° F. and 400 p.s.i.g. with a virgin naphtha feed which had essentially no olefins and gave negligible conversion when passed over the catalyst without pretreatment. The catalytic section was operated at 400 p.s.i.g. and 600° F. with the commercial silica-alumina preparation used in the preceding experiments. The data are:

[Baton Rouge virgin naphtha, 1 liq. v.v./Hr., 400 p.s.i.g., 600° F., silica-alumina catalyst.]

	Feed		Cracking Coll Temp., ° F.	
	Without Treatment	With Cat. Treatment Only	1,000	1,025
Vol. Percent 350° F. + Product.....	0	0	15	17

This demonstrates the feasibility of the two-stage process involving cracking and condensation. Thus, in the absence of olefins, thermal and catalytic treatment of the virgin naphtha gave no product.

Example 5

Typical inspection data on middle distillate samples from various feeds and conditions of operation are summarized as follows:

Catalyst.....	Silica-Alumina			"UOP"	
	Feed.....	Coker Naph.	Catalytic Naph.	Catalytic Naph.	
5					
Feed Rate, V.V./Hr.....	0.5	0.5	1	1	1
Temperature, ° F.....	600	600	500	500	500
Pressure, P.s.i.g.....	800	800	800	800	800
Vol. Percent 350° F. + Product.....	23	16	19.9	18.6	110.5
Inspections 350°-650° F. Prod.:					
Gravity, ° A.P.I.....	35.4	33	33.2	35.9	35.5
Bromine No.....	66	72	68	109	86.0
Aniline Pt., ° F.....	95	82	95.2	97	86.0
Flash Point, Tag, ° F.....		160		144	145

¹ Second pass operation with unconverted naphtha from first cycle.

15 The middle distillate under each set of conditions has a high flash point and is suitable for use as a heating oil. Also, it is possible to use the lower boiling components as jet fuel. The high olefinicity of the "UOP" product as against the SiO₂—Al₂O₃ product is to be noted. High olefinicity is an undesirable property in middle distillates, particularly those that are to be used as fuels, for they are readily susceptible to oxidation and sludging.

What is claimed is:

20 25 1. An improved process for converting paraffinic low octane naphtha into middle distillates which comprises passing said naphtha to a thermal cracking zone, maintaining a relatively low degree of conversion in said zone, forming olefinic hydrocarbons in said zone, passing effluent from said cracking zone to an olefin conversion zone, maintaining a mixed oxide catalyst selected from the group of magnesia-silica and silica-alumina in said zone, maintaining a pressure in the range of from about 600 to 3000 p.s.i.g. and a temperature of about 300° F. to 750° F. in said zone, further maintaining a liquid phase operation therein, keeping said catalyst suspended in said liquid phase, polymerizing and alkylating said effluent in said conversion zone, and recovering good yields of middle distillates.

30 35 40 2. The process of claim 1 wherein 1% to 25% of catalyst, based on feed, is maintained in said conversion zone.

3. The process of claim 1 wherein said thermal cracking operation is carried out at pressures in the range of about 50 to 400 p.s.i.g. and temperatures of about 950°-1150° F.

40 45 4. An improved process for making middle distillates from lower boiling hydrocarbons which comprises passing an olefinic naphtha into a conversion zone, maintaining a liquid phase operation therein, maintaining an alumina-silica catalyst therein, maintaining a temperature of from about 300°-750° F. and pressures of about 600-3000 p.s.i.g., and feed rate of 0.2 to 2.0 v.v./hr. therein, polymerizing and alkylating said olefinic naphtha in said conversion zone, and recovering high yield of middle distillate.

50 55 5. The process of claim 4 wherein virgin naphtha is passed into said zone in admixture with an olefin comprising naphtha.

60 6. The process of claim 1 wherein said liquid phase operation is maintained by recycle of a higher boiling component.
